UNITED STATES PATENT OFFICE.

STANISLAW WILINSKI, OF BAY CITY, MICHIGAN.

APERTURE-CLEANING SYRINGE.

1,399,834.

Specification of Letters Patent. Patented Dec. 13, 1921.

Application filed December 18, 1920. Serial No. 431,581.

To all whom it may concern:

Be it known that I, STANISLAW WILINSKI, citizen of Poland, residing at Bay City, in the county of Bay and State of Michigan, 5 have invented certain new and useful Improvements in Aperture-Cleaning Syringes, of which the following is a specification.

This invention relates generally to a liquid discharge device, having more particular reference to a combination of a 10 syringe element with a discharge nozzle on a pipe or other device conveying a continuous stream.

The invention has for an object to provide a device of this kind whereby momentary increase of pressure of the discharged fluid over that of the continuous stream may be obtained, the invention being suitable for use in cleaning out clogged openings of any 20 kind, such as the overflow openings of sinks, wash-basins, wash-tubs or the like.

For further comprehension of the invention, and of the objects and advantages thereof, reference will be had to the following description and accompanying drawings, and to the appended claims in which the various novel features of the invention are more particularly set forth.

Figure 1 of the drawings is an axial longitudinal sectional view of a device embodying the invention, showing it applied to clean the overflow openings of a wash-basin.

Fig. 2 is a side elevation of the device.

Figs. 3, 4 and 5 are central sectional views 35 of modified forms of nozzle tips.

As here shown my improved device comprises a cylinder 10 which may have a suitable lining element 11 therein and is provided at its forward end with a nozzle cap 12 screwed thereon, the rear end being closed 40 by a plug 13. A pair of finger-grip rings 14 are mounted on the rear portion of the cylinder.

Approximately midway of its length the cylinder 10 is provided with a flanged opening 15, the flange 16 whereof presents an internally threaded socket for the reception of one end of a nipple 17 whose opposite end 45 may be exteriorly conjugated and adapted for insertion in the end of a rubber pipe or hose 18, a split collar 19 being employed to clamp the hose end on the nipple 17. The opposite end of the hose 18 may be connected to a faucet or other source of water 50 supply.

A plunger element 22 is located in the cyl-

inder 10, being of approximately one-half the length of the latter, with its forward end projecting slightly beyond the opening 15 when the plunger is retracted. This 60 plunger 22 is chambered or hollowed out from its front end rearwardly as at 23 and a longitudinal slot 24 is formed in the wall of the plunger and communicates with the interior thereof. The plunger 22 is adapted 65 to be operated by means of a handle 25 fixed on a ring 26 freely surrounding the cylinder 10, this ring having an inwardly projecting screw 27 which is threaded laterally into the solid rear end of the plunger. 70

To accommodate this screw 27 and permit of movement of the plunger 22 with the slot 24 in or out of registry with the opening 15 in the wall of the cylinder 10, the latter is provided with a U-shaped slot the two legs 75 of which, indicated at 28 and 29 respectively, are spaced circumferentially substantially ninety degrees apart and extend forwardly from the connecting transverse portion 30 of the slot. The plunger 22 is normally held 80 in its rearmost position by a coiled expansion spring 31 surrounding the cylinder and bearing at opposite ends between the ring 26 and a flange 32 on the cylinder.

In Fig. 1 of the drawings I have shown 85 my improved device with the nozzle tip 12 directed toward the overflow openings 33 of a wash-basin 34. Assuming the hose to be connected to a faucet from which the water pressure is not very strong, the plunger 22 90 being in position with the slot 24 registering with the opening 15. The pressure can be momentarily increased by hand by quickly pressing the plunger forward with a pressure greater than that of the flowing water, 95 the inertia of the water flowing through the hose 18 acting to resist the tendency of the water to flow backward therethrough when the increased pressure is applied to the plunger. Should it be desired to shut off the 100 opening 15, the plunger can be turned until the screw 27 registers with the slot element 29 and forced forward.

The device may be supplied with the different types of nozzles shown in Figs. 3, 105 4 and 5 which may be employed as desired.

Having thus described my invention what I claim as new and desire to protect by Letters Patent of the United States is as follows:

1. A device of the class described comprising a cylinder, having an intake opening be-

tween its ends, a discharge nozzle on said cylinder, a chambered plunger within said cylinder having a slot in its side wall and having its rear end closed, and means whereby said plunger may be advanced with the said slot in or out of registry with the said opening.

2. A device of the class described comprising a cylinder, having an intake opening between its ends, a discharge nozzle on said cylinder, a chambered plunger within said cylinder having a slot in its side wall and having its rear end closed, and means whereby said plunger may be advanced with the said slot in or out of registry with the said opening, said means including a handle element projecting through a U-shaped slot in the wall of the cylinder.

3. A device of the class described comprising a cylinder having an intake opening between its ends and a U-shaped slot the legs of which extend forwardly, a chambered plunger in said cylinder having a longitudinal slot in its side wall and having its rear end closed, a ring surrounding said cylinder, a member projecting inwardly from said ring, through the said U-shaped slot to fix the ring to the said plunger and adapted when engaged with the different legs of the

said U-shaped slot to position the slot in the 30 plunger respectively in or out of registry with the said intake opening, and a spring bearing against said ring.

4. A device of the class described comprising a cylinder having an intake opening approximately midway of its length, and a U-shaped slot located rearwardly of said intake opening, the legs of said slot extending forwardly and being spaced apart approximately ninety degrees, a discharge nozzle on said cylinder, a chambered plunger in said cylinder of approximately one-half the length of the latter, and having a longitudinal slot in its side wall and its rear end closed, a ring freely surrounding the plunger, a handle fixed on said ring, a screw projecting inwardly from said ring to said plunger through the said U-shaped slot and fixed to said plunger and adapted when engaged with the different legs of the said U-shaped 50 slot to position the slot in the plunger respectively in or out of registry with the said intake opening, and a coiled expansion spring surrounding said cylinder and bearing against said ring.

In testimony whereof I have affixed my signature.

STANISLAW WILINSKI.
